UNITED STATES PATENT OFFICE.

CLINTON A. TANSLEY, OF FORT PLAIN, NEW YORK, ASSIGNOR OF ONE-HALF TO CARL H. GREENE, OF FORT PLAIN, NEW YORK.

OAR-LOCK.

SPECIFICATION forming part of Letters Patent No. 695,011, dated March 11, 1902.

Application filed July 29, 1901. Serial No. 70,160. (No model.)

To all whom it may concern:

Be it known that I, CLINTON A. TANSLEY, a citizen of the United States, residing at Fort Plain, in the county of Montgomery and State 5 of New York, have invented a new and useful Oar-Lock, of which the following is a specification.

This invention relates to oar-locks; and the object of the same is to provide simple and effective means in the construction of an oar-lock to afford an oarsman every facility for handling his oar with dexterity and plying in the water in the several evolutions of feathering, carrying, and in shipping, as well as convenience in application in a reliable manner.

The invention consists in the construction and arrangement of the several parts, which will be more fully hereinafter described and claimed.

20 In the drawings, Figure 1 is a side elevation of a portion of a boat, showing the improved oar-lock applied thereto and having a portion of an oar therein in shipped or partially-shipped position. Fig. 2 is a perspective view

25 of the improved oar-lock. Fig. 3 is a transverse vertical section of the improved oar-lock, showing parts in elevation.

Similar numerals of reference are employed to indicate corresponding parts in the several 30 views.

The numeral 1 designates an upper table, having a concave recess 2 in the upper side thereof to receive the oar-shank and also provided with diametrically-opposed ears 3, 35 an under recess 4, surrounding a depending screw-threaded post 5 at the center, and a peripheral flange 6. The said upper table is mounted on a lower table 7, having a peripheral shoulder 8 to loosely receive the flange 6 40 of said upper table and also having an upper recess 9, which will be contiguous to the recess 4 when the two tables are operatively disposed in relation to each other. Through the center of the table 7 a vertical opening 10 45 is formed to permit the post 5 to extend through said lower table, and at diametrically opposite points the latter has depending bearing-arms 11, between which the upper apertured head 12 of a thole-pin 13 is pivotally 50 mounted and held by a bolt 14, passing therethrough and through the said arms, the said

bolt being provided with a removable nut 15 for convenience in assemblage and disconnection of the said parts. The thole-pin is square in cross-section and is fitted in a similarly-shaped socket secured to or formed in the rail or other upper portion of the gunwale of the boat to prevent the said thole-pin from turning, though said pin may be inserted in or withdrawn from its socket, as may be desired. 60

The recesses 4 and 9 form seats or races for steel balls 16, and when the two tables are assembled they are held against disconnection by a nut 17, engaging the lower end of the post 5 between the upper portions of the 65 arms 11. It will be seen that the two tables are free to unitedly swing on the head of the thole-pin and that the upper table is permitted to horizontally rotate on the lower table to accommodate the variety of evolutions or 70 movements of the oar in carrying into effect the several operations of feathering, carrying, and shipping, as well as allow the blade of the oar to catch as deep in the water as may be desired by the oarsman. 75

The oar-shank is held in the concave recess 2 of the table 1 by an arcuate yoke 18, which is applied diametrically across and above the said table 1 through the medium of lower terminal screw-stems 19, removably 80 fitted in the ears 3 and maintained against accidental disconnection by nuts 20. The yoke 18 may be easily applied and disconnected, and it may also be secured to tightly clamp the oar-shank or be made loose enough 85 to permit the shank of the oar to turn therein. The degree of binding of the yoke will be regulated by the choice of the oarsman, the character of the oar, and the motion desired to be imparted to the latter. It will be 90 noticed that the oar when applied in the improved lock will be prevented from becoming disengaged, and, moreover, the yoke can be placed directly over the portion of the oar-shank desired without requiring longitudinal 95 movement of the oar to properly dispose the same.

The improved lock is strong and durable, sensitive in its movements, and readily applicable to a boat, and though the preferred 100 form of the same is shown it is obvious that changes in the form, size, proportions, and

minor details can be resorted to without departing from the principle of the invention.

Having thus described the invention, what is claimed as new is—

- 5 1. An oar-lock having an upper horizontally-rotatable table also capable of a swinging movement, and an arcuate yoke having lower terminal screw-stems removably applied to diametrically opposite portions of the said table.
- 10 2. An oar-lock having an upper horizontally-rotatable table also capable of a swinging movement, and an arcuate yoke having its terminals removably attached to said table.
- 15 3. An oar-lock having an upper horizontally-rotatable table provided with a central depending screw-threaded post, an arcuate yoke removably attached to said table, a lower table through which the said post ex-

tends and is secured, the said lower table having depending bearing-arms, balls interposed between the tables, and a squared thole-pin having a head pivotally held between the said arms.

4. An oar-lock having an upper table provided with clamping means for an oar-shank, and also having a central depending post, a lower pivotally-held table through which said post projects and is secured, and balls interposed between the two tables.

In testimony that I claim the foregoing as my own I have hereto affixed my signature in the presence of two witnesses.

CLINTON A. TANSLEY.
